UNITED STATES PATENT OFFICE.

OSROE A. CLARK, OF NEWARK, NEW JERSEY.

SAFETY-RAZOR.

933,020.

Specification of Letters Patent. Patented Aug. 31, 1909.

Application filed January 9, 1909. Serial No. 471,466.

To all whom it may concern:

Be it known that I, OSROE A. CLARK, a citizen of the United States, residing at Newark, in the county of Essex and State of New Jersey, have invented certain new and useful Improvements in Safety-Razors; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

15 This invention relates to a safety razor that comprises a handle portion which is screwed on a screw-threaded stem on a face plate, and these two, when screwed together, hold between them a guard and a blade so 20 that the blade, which has preferably two opposite cutting edges, can be used for shaving in conjunction with the guard so as to prevent cutting the operator.

The invention is particularly designed to 25 provide co-acting means on the guard and on the face plate to hold the face plate and the backing in register and to position them when they are assembled, and also to provide the blade with a perforation to permit the 30 assembling of the parts through the blade and to also permit the blade to surround the positioning means or the co-acting means for holding the guard and the face plate in register so that the blade is also held in its 35 proper position with its edges in parallel relation with the edges of the guard. The co-acting means for holding the parts in register are arranged on the opposed faces of the guard and the face plate and pass only 40 through the blade and not through each other so that the expensive perforation of parts is obviated, and there are also no unseemly projecting portions, whereby the exterior is smooth and without any protuberances.

The invention is illustrated in the accompanying drawing, in which—

Figure 1 is a top view of the razor. Fig. 2 is a side view of the same, one half of the 50 blade-holding portion being shown in section. Fig. 3 is a cross-section through the center of the razor showing the handle in elevation. Fig. 4 is a perspective view of the razor with its parts separated, but showing the handle up close to the guard.

The device comprises a guard 10 which is preferably formed with an upper face to form a flat bearing surface for a blade and has teeth 11, which teeth are preferably arranged on the two opposite edges, since the 60 duplication of edges, which is not essential, gives more utility to the device. On the guard is placed a blade 12 which has its two opposite edges 13 sharpened to form cutting edges, which edges are adapted to co-act 65 with the teeth 11 and form the safety cutting edges. The blade is also provided with a perforation 14 which is made of a contour substantially the same as a projection 15 on the guard so that when the blade is set down 70 over this projection, it is held against any twisting, and the edges of the guard and the edges of the blade are bound to be parallel. The guard is perforated as at 16, which perforation receives a screw-threaded post 17 75 which projects from the face plate 18, which face plate has a curved outer surface 19 to give it a smooth face on the portion that comes in contact with the operator's face. The portions 20 of the face plate 18 rest 80 down on the ends of the blade 12, as shown in Fig. 2, and hold the blade strictly in position, the face plate being recessed as at 21 to receive the ends of the projection 15 so that when the face plate is in position on top 85 of the blade and the guard, it is also held against any twisting, and its edges are also insured in their parallel relation with the edges of the blade and the edges of the guard. A handle 22 has a shoulder 23 which 90 is pressed up against a flange 24 on the guard, and it also has a screw-threaded recess 25 which receives the screw-threaded post 17, and when the handle is turned all 95 the parts are locked in their position.

When the razor is to be assembled, the face plate and the blade are placed together with the co-acting means on the face plate and on the guard operating to hold the parts together, and the blade, by means of its perforation, surrounding the co-acting means, and then the handle is screwed onto the post 100 17 and the whole is made into one structure, forming a smooth exterior at all points and having no projections, which makes the device more easily cleaned. The blade and the face plate are preferably made of the same contour, particularly on their ends, but are made slightly longer than the guard so that 105 when the handle 22 is unscrewed, the blade 110

and the face plate can be taken from the guard together and then separated one from the other afterward. It also provides an easy means for holding the blade and the face plate by means of the thumb and forefinger of one hand, when they are assembled, and they are thus held in register while being placed over the projection 15 of the guard.

10 Having thus described my invention, what I claim is:—

15 1. A safety razor comprising a guard having a substantially centrally arranged perforation, a projecting portion on the face of the guard and extending both sides of the perforation, a blade having a single perforation to receive the projecting portions on the guard, a face plate having a recess on its inner face to receive the projections on the guard, a screw-threaded stud on the face plate adapted to pass through the perforation in the guard to approximately center the face plate on the guard and on which the face plate can be swung to seat itself on 20 the projection of the guard, and a handle to bear on the under side of the guard and re-

ceive the screw-threaded stud to secure the parts together.

2. A safety razor comprising a guard having a substantially central perforation, a projecting portion on the face of the guard and extending on both sides of the perforation, a blade having a single perforation to receive the projection on the guard, a face plate having a recess on its inner face to receive the projections on the guard, the blade and the face plate being longer than the guard to permit the fingers to pass the guard so that the face plate and blade can be seated at the same time on the projection on the guard, a screw-threaded stud passing through the perforation in the guard, and a handle to receive the stud to secure the parts together. 35

In testimony, that I claim the foregoing, I have hereunto set my hand this 6th day of January 1909. 40
